[57] ABSTRACT

A gauze electrode for a cathode-ray tube, in particular a camera tube, in which the aperture of the supporting ring is substantially rectangular the oppositely located sides of which are curved.

GAUZE ELECTRODE FOR A CATHODE-RAY TUBE

The invention relates to a gauze electrode for a cathode ray tube, which electrode is arranged at a small distance parallel to a signal plate and which is supported at the edge by at least one supporting ring, measures being taken to reduce "microphony" interferences which may occur as a result of vibrations of the gauze electrode. The invention relates in particular to a gauze electrode for a camera tube of the vidicon type.

It has already been tried in various manners to reduce the "microphony" effect of such a gauze electrode, for example, by providing rods or plates which, if desired, also serve as spacing members between gauze and signal plate (see British Patent Specification Nos. 984,673; 948,944 and 1,094,186) or by reinforcing the gauze by providing ribs in the gauze (German Patent Specification No. 1,237,168). However, these known measures are complicated and attenuate the vibrations of the gauze electrode only to an unsatisfactory extent.

A much simpler solution which provides a much stronger attenuation of the undesired vibrations of the gauze electrode is obtained if, according to the invention, the inner edge of at least one supporting ring of the gauze electrode encloses an aperture which mainly is in the form of a rectangle of which at least two oppositely located sides are curved, the wires of the gauze extending mainly according to the diagonals of the rectangular aperture. The corners of the rectangle are preferably rounded off, so as to be able to better use the surface of the gauze. The curved sides of the aperture preferably extend convex relative to the centre of the aperture. Preferably, all four sides are shaped in this bent manner. The radius of the curved sides is preferably approximately equal to the radius of the outer edge of the supporting ring.

A damping member of thin aluminum foil is known from the U.S. Pat. No. 3,287,585 which is provided as a spacing member between gauze and signal plate. It is stated that the aperture of said foil may be irregular and that finger-shaped projections may be present, if desired. However, such projections can only be used if the material thereof consists of a thin foil since otherwise they damage the gauze.

The invention will be described in greater detail with reference to the accompanying drawing, of which:

FIG. 1 is a longitudinal sectional view of a vidicon tube,

FIG. 2 shows an embodiment of a supporting ring for a tube with rectangular picture scanning, and

FIG. 3 shows an embodiment of a supporting ring suitable for scanning both a rectangular and a circular disk-shaped picture, while

FIG. 4 is a part of a cross-sectional view of a gauze electrode according to the invention.

Reference numeral 1 in FIG. 1 denotes the wall of a vidicon camera tube which is closed by a glass plate 2. A photosensitive signal electrode 3 is present on the inside of the plate 2. The gauze electrode 4 is provided parallel to the electrode 3 and at a few millimeters distance therefrom. The gauze 4 consists, for example, of wires of nickel or copper having a thickness of 4μ and a center distance of 36μ . Instead of wires, the gauze electrode 4 may also be a perforated plate.

The gauze 4 is clamped between two supporting rings 5 and 7 which are secured together by means of a num-

ber of spot welds along the circumference or by soldering or diffusion. The material of the ring 5 has a thickness of, for example, 0.5 mm, the material of the ring 7 is, for example, 0.1 mm thick. The rings 5 and 7 consist of molybdenum when nickel gauze is used and of a chromium-nickel alloy when copper gauze is used. Furthermore, an electron lens 6 is provided in the tube.

The supporting ring 7 shown in FIG. 2 comprises a mainly rectangular aperture the sides 8 and 9 of which are convex relative to the center of the aperture. The corners are rounded so as to obtain a better use of the gauze surface. The sides 9 are longer than the sides 8 so that this electrode is mainly suitable for scanning an elongate rectangular picture surface.

In the embodiment shown in FIG. 3, all sides 8 of the aperture are the same so that this electrode is suitable both for scanning circular disk-shaped pictures and for scanning rectangular pictures. The wires of the gauze 4 extend approximately according to the diagonals of the mainly rectangular aperture. In the case in which the gauze electrode consists of a perforated plate, the holes are provided in rows which extend approximately in the direction of the diagonals of the mainly rectangular aperture of the ring.

As is shown in FIG. 4, the parts of the sides 8 and 9 projecting inwardly may be bent out of the plane of the ring so that they slightly press on the gauze 4 and thus intensify the damping effect. It has been found that the damping of a ring formed according to the invention is approximately 20 times more effective than in the case in which a ring 7 is used having a rectangular hole with straight sides.

Although two particular embodiments of the invention have been described, other shapes for the aperture of the ring 7 may be used without departing from the scope of this invention. For example, a rectangle may be used having two straight and two oppositely located curved sides, or the corners may not be rounded off, in which case a cushion-shaped aperture is formed. The use of an aperture having more than 4 sides is more unfavourable according as the number of sides increases, since the circumference of the aperture increasingly approaches the circle, which is unfavourable with respect to the occurrence of vibrations.

Besides for camera tubes, the invention is also of importance for other cathode-ray tubes, for example, oscillograph tubes, and the like.

What is claimed is:

1. In a cathode-ray tube having a target electrode at one end of an envelope and a gauze electrode spaced from said target electrode, the improvement comprising at least one annular member spaced from said target for supporting said gauze electrode with reduced microphonic interference, said annular member having an inner edge enclosing a substantially rectangular aperture having at least two oppositely located curved sides, said gauze electrode comprising wires extending substantially parallel to the diagonals of said rectangular apertures.

2. A gauze electrode as claimed in claim 1, wherein the rectangular aperture has rounded corners.

3. A gauze electrode as claimed in claim 1, wherein the curved sides are convex towards the center of the aperture.

4. A gauze electrode as claimed in claim 3, wherein the convex shaped parts of the supporting ring are bent out of the plane of the ring in the direction of the gauze.

5. A gauze electrode as claimed in claim 4, wherein the radius of the curved sides is approximately equal to the radius of the outer edge of the supporting ring.
